UNITED STATES PATENT OFFICE.

JOHN DILLON, OF HACKENSACK, NEW JERSEY.

HORSESHOE-PAD.

No. 909,287.

Specification of Letters Patent.

Patented Jan. 12, 1909.

Application filed March 27, 1908. Serial No. 423,671.

To all whom it may concern:

Be it known that I, JOHN DILLON, a citizen of the United States, residing at Hackensack, in the county of Bergen, State of New Jersey, 5 have invented certain new and useful Improvements in Horseshoe-Pads; and I do hereby declare the following to be a full, clear, and exact description of the invention, such as will enable others skilled in the art to 10 which it appertains to make and use the same.

This invention relates to a new and useful improvement in horseshoe pads.

The object of my invention is to provide a 15 pad adapted to be used in connection with horseshoes and is more particularly intended as an improvement upon the invention secured to me in U. S. Letters Patent No. 837,808, for an improvement in horseshoes, 20 patented Dec. 4, 1906. In said Letters Patent I disclose a retaining plate provided with certain perforations and describe as secured to opposite sides of said plate two elastic 25 cushions, these cushions being secured by means of cement plugs.

In my present invention, I dispense with the operation of cementing the two rubber sections together in that I provide the retaining plate with suitable openings, and 30 then cast or otherwise secure an upper and lower cushion section to the retaining plate, by any suitable means, the two sections being connected by means of integral portions extending through the plate openings.

35 A further improvement is embodied in my present invention, in that I stamp up certain portions of the retaining plate, to form up-standing shoulder forming web portions which may be directed in opposite directions 40 or be extended at right angles or at an acute angle, these shoulder forming webs assisting in holding the lower cushion against accidental displacement as well as prolonging the life of the pad, in more securely holding 45 the cushion to the retaining plate.

In the accompanying drawings, like characters of reference indicate like parts in the several views, and:—Figure 1 is a bottom plan view of a horseshoe pad constructed in 50 accordance with my invention. Fig. 2 is a top plan view of the plate used therewith. Fig. 3 is a top plan view of the complete pad. Fig. 4 is a central sectional view through the complete pad.

55 In carrying out the aim of my invention,

I use a suitable metal plate 10, in outline conforming to the shape of a horseshoe. This member forms a retaining plate by means of which the cushion or elastic portion of the pad is secured to the animal's 60 hoof, or to a suitable horseshoe. This plate may be a metal plate or it may be made of leather or other material.

The retaining plate 10 is provided with a series of rectangular openings formed by 65 incising the plate around three edges of the openings and striking out the metal to form a plurality of oppositely projecting lugs 6. Upon the retaining plate so formed is an 70 elastic cushion A cast upon both sides of the plate 10 so that the upper and lower cushion portions are connected by the cushion portions within the openings 5. These cushion portions are of such thickness as to entirely 75 cover the lugs 6 on both sides of the plate. The cushions A are further formed so that 80 the retaining plate is provided with an uncovered perforated securing edge 12, the perforations 3 and 4 being adapted to receive the screw calks by means of which the pad is secured to the shoe. There has thus been provided a simple and efficient device of the kind described and of the character specified.

I claim—

85 A horseshoe pad comprising in combination, a perforated metal plate in outline conforming to the shape of a horseshoe, said perforations being formed by incising and striking out the metal to form a plurality 90 of oppositely projecting lugs, said plate having two toe calk openings and two heel calk openings, an elastic cushion cast upon both sides of said plate and through said perforations to entirely cover said lugs and forming 95 an upper and a lower cushion, said lower cushion being of such an outline that an uncovered plate space is provided around said calk openings, the face of said lower cushion being flat, the upper face of said plate having 100 an uncovered edge to receive the horseshoe, said upper cushion being bevel edged and having a central longitudinal groove, all arranged as disclosed.

In testimony whereof, I affix my signature, in presence of two witnesses.

JOHN DILLON.
